UNITED STATES PATENT OFFICE.

RUDOLPH MESTEK, OF PIERCE, WEST VIRGINIA.

DIRECTION-INDICATOR.

1,294,932.

Specification of Letters Patent. Patented Feb. 18, 1919.

Application filed August 19, 1918. Serial No. 250,489.

To all whom it may concern:

Be it known that I, RUDOLPH MESTEK, a citizen of the United States, residing at Pierce, county of Tucker, and State of West Virginia, have invented certain new and useful Improvements in Direction-Indicators, of which the following is a specification.

This invention relates to improvements in street indicators as used upon railway vehicles for showing the location at which the car will next stop.

The principal object of the invention is to provide a device which is operated indirectly by the motive power of the vehicle, and which visibly displays a sign indicating the next stopping place.

This and other like objects are attained by the novel construction and combination of parts hereinafter described and shown in the accompanying drawings, forming a material part of this disclosure, and in which—

Figure 1 is a fragmentary vertical sectional view, showing a conventional type of car and indicating the application of the invention.

Fig. 2 is a transverse sectional view taken on line 2—2 of Fig. 1.

Fig. 3 is a front elevational view of the indicator, the cover plate being removed.

Fig. 4 is an end view of the same.

Fig. 5 is a vertical sectional view taken on line 5—5 of Fig. 3.

Fig. 6 is a similar view taken on line 6—6 of Fig. 3.

Fig. 7 is a longitudinal sectional view, taken through one of the indicator rolls, and

Fig. 8 is a sectional view showing the details of the finger by which the ratchets are operated.

Referring to the drawings, the numeral 10 indicates the flooring of a conventional type of car, the same being supported upon wheels 11 engaged with the axles 12 as usual. Attached centrally to one of the axles 12 is a spur gear 14, meshing with a mating gear 15, fixed upon a spindle 16, mounted in supports 17 and carrying spools 18 upon each side provided with flanges 19 upon which are wound wires 20.

These wires pass over guide pulleys 22 through the flooring 10 and extend upward through the car body to the indicator casing 25, having a removable cover plate 26, through which are formed elongated open-

ings 27, normally covered by transparent plates 28, rearward of which are a pair of oppositely inclined, deflecting plates 29.

A pair of bosses 30 extend inwardly from one end of the casing 25 and substantially 60 central between them is a similar boss 31.

Held in the bosses 30, by the set screws 32, are horizontal rods 33 and 35 respectively upper and lower, upon which are engaged disks 36 and 36', forming the ends of drums 65 or rollers upon which is rolled a strip of fabric 38 bearing the names of streets or points at which the car makes stops.

The outer ends of the rods 33 and 35 are rotatable within the hubs of the disks 35' 70 which are driven by connections with stub spindles 33' and 35', on which are engaged ratchet wheels 39 and 40 adjacent to the disks 36', while upon the outer ends of the stub spindles, adjacent to the inner surface 75 of the casing 25, opposite to the bosses 30, are other ratchets 41 and 42, their teeth being in an opposite direction, for purposes which will be hereinafter described.

Mounted in the central base 31 is a spindle 44 extending into the boss 45 formed with the opposite end of the casing, and fixed upon the spindle 44 is a grooved pulley 47 over which the flexible wires 20 make contact, the bight of the wire passing over 85 the pulley 48, freely pivoted within the casing as shown in Figs. 3 and 6.

Fixed upon the spindle 44, adjacent to the pulley 47, are eccentrics 49 and 50 from the former of which extends a pawl 51 passing through an adjustable guide 53 and held normally in contact with the teeth of the ratchet 39 by the plate spring 61.

Extending in the opposite direction from the cam 50 is a similar pawl 52, guided in 90 the adjustable bracket 54, normally pressed forward by the plate spring 62. The brackets 53 and 54 are attached to the ends of the levers 57 and 58 by stems 55 and 56 through 95 wall of the casing and provided with handles by which they may be operated.

Thus as the wire 20 moves intermittently in one direction it will cause the pawls 51 and 52 to be engaged with the ratchet wheels 39 and 40, according to the position of the 100 levers 57 and 58.

Communicating rotary motion to the disks 36' causes the rollers to rotate upon the rods 33 and 35, which are held tensionally against rotation, due to the effect of 110

2
coiled torsional springs 63, within the tubular centers 64 of the rollers, one end of the springs being secured to the disk 36', and the other end to collars 65 rigidly secured 5 to the rods.

In order to prevent the rollers from operating in a direction reverse to that desired, other pawls 70 and 71 are carried on stems extending through the end of the casing and 10 operatively engaged with levers 59 and 58, provided with extending handles, the pawls being engageable with the ratchet wheels 41 and 42 respectively, the same being fixed on the ends of the stubs 33' and 35'.

15 In operation when the car is moved in one direction motion will be transmitted by the axle, through the gears, and due to the frictional engagement of the flexible wire 20, the cam spindle 44 will be rotated, which 20 moves the pawls into engagement with the ratchets, causing either of the stubs 33' or 35' to rotate, and it will be evident that by properly positioning the handles extending from the end of the casing, that the strip 25 may be moved in either direction at will and prevented from reverse action.

Having thus described my invention, what

I claim as new and desire to secure by Letters Patent, is—

In a direction indicator, the combination 30 with a rectangular casing having an opening through one of its outer sides, a pair of rods mounted longitudinally in said casing, a shaft rotatably mounted midway between said rods, a pulley on said shaft, a flexible 35 wire engaging with said pulley, means combined with the vehicle for operating said flexible wire when the vehicle is moving, rollers on said rods, a strip of fabric wound upon said rollers, said strips bearing the 40 designation of the stopping places of the vehicle, ratchet wheels engaged upon the ends of said rods, cams on said shaft, pawls operated by said cams, means on said casing for moving either of said pawls into or out 45 of engagement with said ratchet wheels, said means extending through said casing whereby said strip is caused to move in either of two directions, and means contained within said rollers whereby said strip is normally 50 held in a taut condition.

In testimony whereof I have affixed my signature.

RUDOLPH MESTEK
